UNITED STATES PATENT OFFICE.

FRANK KUHN AND JAY A. HAND, OF DETROIT, MICHIGAN, ASSIGNEES TO AMERICAN ELECTRICAL HEATER COMPANY, OF DETROIT, MICHIGAN, A CORPORATION OF MICHIGAN.

ELECTRIC COOKING-RANGE.

1,376,208.

Specification of Letters Patent. Patented Apr. 26, 1921.

Application filed February 21, 1918. Serial No. 218,407.

To all whom it may concern:

Be it known that we, FRANK KUHN and JAY A. HAND, both citizens of the United States of America, both residing at Detroit, 5 in the county of Wayne and State of Michigan, have invented certain new and useful Improvements in Electric Cooking-Ranges, of which the following is a specification, reference being had therein to the accompanying drawings.

The invention relates to electric cooking ranges, and has reference to various features of construction as hereinafter set forth.

In the drawings:

15 Figure 1 is a front elevation of the range; Fig. 2 is a cross-section substantially on line 2—2 Fig. 1;

Fig. 3 is a top plan view;

Fig. 4 is a vertical cross-section on line 20 4—4 Fig. 1;

Fig. 5 is a perspective view showing one of the cover plates for the top section of the range.

Our improved range comprises a top section having a plurality of surface heating units; also ovens arranged at one side of the top section and having independent units. The switches controlling the several units are all arranged in front of the top section and are suitably marked to designate the particular units which are controlled thereby. One of the features of the invention is the construction and arrangement of mounting for these switches and the association therewith of fuse cut-outs in such relation that the operator may conveniently replace a blown fuse without detailed knowledge of the construction of the range. Another feature is the manner of mounting the heating units on the top section so that they may be easily interchanged. These units are of a type in which a naked resistor is placed in a grooved refractory plate, and our improved construction provides for the protection of the unit while permitting the exchange.

In detail, A is the top section having the back-plate B, and the oven C at one end thereof beneath which is arranged a broiler oven D. E is a shelf extending along the back at the level of the top of the oven C, the general arrangement being similar to that of gas ranges. The top section A is

formed by a marginal frame F preferably formed of angle bars with an intermediate 55 division bar F', and with pairs of supporting bars G G' G² G³ for the several heating units, said bars being below the level of the top of the frame and being secured at their ends to the angle bars F.

The units H for the top section of the range are preferably formed of circular blocks H' of refractory material having grooves H² therein, in which the resistor is placed. The upper faces of the blocks lie 65 flush with the open top, and to provide against cracking and dropping away of the refractory material each block is set in a metal pan I which rests upon the bars G G', etc. J are cover plates for the space 70 surrounding the units, these being preferably rectangular in form and centrally cut away to fit about the unit. Externally these plates are all of the same dimensions and are therefore interchangeable, but the central 75 apertures are formed to receive units of various sizes. The plates J are secured in position by spring clip members J' depending therefrom and having a snap engagement with the bars F and F'. The clips 80 J' are preferably detachably engaged with the plates J by providing the latter with straps J² riveted or spot-welded to the underside of the plate, which permits of replacing a broken clip when necessary. 85 When all of the cover plates are in position the entire space between units will be covered and the cover plates will be flush with the tops of the units.

As above stated, all of the units of the 90 top section as well as those for the oven are controlled by switches arranged in front of the top section. These switches K are mounted upon a bar K' secured to supporting brackets K², the arrangement being 95 such that the switches are inclined upward and are horizontally in line with each other. In front of these switches is a detachable cover plate L similarly inclined and having depressed portions L' forming recesses 100 in which the switch handles are located. This will protect the handles from catching upon the clothing of the operator, and the plate L may also have marked thereon suitable indications for the switches.

Below the switches K there is a compart-

ment which is formed above the main frame M, supporting the top section and ovens. In this compartment are arranged the fuse cut-outs N which are in line with each other and are vertically in substantial alinement with their respective switches. Suitable electrical connections are made to these fuse cut-outs from the service line and from the cut-outs to the switches. The conductors 10 from the switches in turn lead to the several heating units both in the open top section and in the ovens. These conductors are protected from water or any other material on the top, first, by the cover plates J, and 15 further by a pan O which is arranged beneath the bars G G', etc. O' are insulator blocks which pass through and are sealed into the bottom of the pan O and through which the conductors P for the top units 20 are passed. These conductors are carried upward and are secured to the terminal contacts P' of the units, which latter are not secured to the frame but merely rest in the pans I upon the bars G G', etc. The construction is therefore one which permits of 25 quickly detaching and replacing the unit, or exchanging the units in positions so that where they are of different sizes they may be arranged wherever most convenient. 30 This arrangement is also permitted by making all of the cover plates J interchangeable, as previously described.

The ovens C and D are also provided with heating units, there being a unit Q for the 35 bottom of the oven C and a unit R which may be interchangeably positioned at the top of the oven C and at the top of the oven D. The units Q and R are provided with terminal contacts S at their rear ends, 40 which are engageable with sockets S' placed in the rear wall of the oven. This rear wall as well as the side walls of the oven is formed of spaced metal plates T T', with thermal insulating material T² in between, 45 and the blocks S are of a length to pass through the wall with their inner ends substantially flush with the inner metallic lining. In rear of the wall T and spaced therefrom is a false back U which forms an air 50 chamber for additional heat insulation, and also a space in which the electrical connections can be passed. The back U is provided with one or more removable pans U' to facilitate ready access to the electrical connections. 55

Intermediate the upper and lower ovens C and D there is a partition wall V having thermal insulation V' therein. The bottom of the door opening for the upper oven is 60 above the partition V so as to form a pocket V² in which the unit Q is placed, and above this unit there is a pan and shield W which deflects the air heated by the unit to the opposite sides of the oven. The unit R is 65 supported by guide flanges X at the top of

the ovens C and D, which also guide the unit inward with the terminals in registration with their sockets.

It is desirable to clearly indicate whenever current is passing through any of the 70 several circuits and the best indication is an electric light. Inasmuch, however, as the units when all in operation draw a relatively heavy current it is impractical to place a signal light in series therewith. We have 75 therefore provided a controlling device by which the passage of current from the main line to one or more of the units will close a separate circuit for the signal lamp. This controller preferably consists of an electro-magnet Y having a heavy coil capable of carrying the maximum current drawn by the range and an armature Y' which when attracted by the magnet will close the electric circuit Y² including the signal light Z. This 80 signal light is preferably mounted in a socket beneath the shelf E, and the front rail E' on the shelf is cut away at E² to form a window, preferably covered with red glass. The controller may be placed in the same 85 compartment which contains the fuse cut-outs N, where it will be protected from injury and at the same time is accessible for adjustment or repairs.

With the construction as described in use, 90 the top section of the range may be used in the same manner as a gas or coal range, and the several units are controlled by switches in front thereof. There are also adjacent switches which control the units for the 100 ovens. Whenever any one of the switches is turned on, the circuit for the signal light Z will be closed by the controller Y and the illumination will continue as long as any unit is in operation. Should water or any 105 other material be spilled upon the top it is prevented from finding access to the electrical connections by the cover plates J and the pan O. The cover plates may be removed whenever necessary, and if it is desired to 110 exchange the positions of the units this may be quickly accomplished and the cover plates correspondingly exchanged.

The arrangement of the unit Q in the pocket V² in the oven bottom provides full 115 space within the oven equal to the area of the door opening. If it is desired to obtain access to the switches the plate L may be quickly removed, while access to the fuse-cut-outs N is obtained through a door N' 120 covering the compartment in which they are placed.

What we claim as our invention is:

1. In an electric stove, the combination 125 with an open rectangular frame, of a plurality of heating units supported on said frame, and a plurality of shields apertured to receive the respective units and interchangeably mounted on said frame to close the open spaces thereof. 130

2. In an electric stove, the combination with an open rectangular frame, of a plurality of heating units varying in size, interchangeably arranged within said frame, 5 and rectangular shields, apertured to engage the respective units interchangeably, mounted on said frame to cover the open spaces of different portions thereof.

3. In an electric stove, the combination 10 with an open rectangular frame, of a shield or closure for said frame formed of a plurality of interchangeable rectangular sections, and interchangeable heating units varying in size engaging different sections 15 of said shield.

4. In an electric stove, the combination with an open frame, of a heating unit supported within said frame, a shield or cover surrounding said unit and closing the open 20 spaces of said frame, and snap engagement means for retaining said shield upon said frame.

5. In an electric stove, the combination 25 with an open frame, of an electrical heating unit supported within said frame, a shield apertured to surround said unit and covering the open spaces of said frame, and

a plurality of spring clips depending from said shield and having a snap engagement with said frame.

30

6. In an electric stove, the combination with a frame having a top section and an oven section adjacent thereto and extending thereabove, of a pocket formed in the bottom of said oven below the level of said frame, an electrical heating unit in said pocket, and a shield or bottom above said heating unit.

35

7. In an electric stove, the combination with a frame having a top section, of an oven supported on said frame provided with heat insulating walls, a heating unit for said oven having terminal contacts at the rear thereof, an electrical insulator arranged within the heat insulation of the rear wall 45 of said oven provided with socket contacts for engagement with the contacts on said unit, a false back for said frame, and electrical conductors passing between said oven and false back.

50

In testimony whereof we affix our signatures.

FRANK KUHN.
JAY A. HAND.
